OP D 13.539

Design No. 13,539, dated January 23, 1863.

UNITED STATES PATENT OFFICE.

NICHOLAS BRAYER, OF ROCHESTER, NEW YORK, ASSIGNOR TO THE CO-OPERATIVE FOUNDRY COMPANY, OF SAME PLACE.

DESIGN FOR A HEATING-STOVE.

SPECIFICATION forming part of Design No. 13,539, dated January 23, 1863.

Application filed October 24, 1862. Term of patent 7 years.

To all whom it may concern:

Be it known that I, NICHOLAS BRAYER, of Rochester, in the county of Monroe and State of New York, have invented a Design for 5 Heating-Stoves, of which the following is a specification.

My design embraces a body having in cross-section substantially the form of an oblong rectangle, with the corners beveled or chamfered.

The design consists of five principal sections—to wit, the base, the ash-pit, the grate, the fire-pot, and the top or magazine.

The design for the base A consists substantially of a flat rectangular plate with beveled corners and substantially vertical smooth edges a, terminating in a bead or lip, b, extending around the lower edge. Beneath the plate A a depending flange, c, is located, the lower edge

20 of this flange being of curved outline, as shown.

At the corners of the flange c sustaining legs e, of the curved form shown, are arranged. The upper surface of the plate a and the outer surfaces of the flange c are provided with ornamental lines in intaglio, as represented in

25 the drawings.

B represents the ash-pit section, with vertical walls of an outline corresponding with the marginal form of the plate a. The section B

30 is provided at its two ends with raised panels f, the corners of which are chamfered and indented, as shown, and the outer surface of

which is provided with intaglio ornaments, as shown. Each of the four beveled corners of

35 the ash-pit section B is also provided with a raised panel, g, beveled at the corners and provided with an ornamental figure in intaglio, the figure representing a vase or urn with growing plants therein. The section B has at

40 its front a hinged door, h, provided with vertical openings, which are closed on the back by the damper-plate j. The openings are encircled by a raised bead, and the outer surfaces of the door and the damper-plate are both

45 provided with intaglio figures, such as shown.

The top of the base portion is formed by a substantially flat plate, k, the edges of which overhang the section B on its several sides, as shown. The plate k has a substantially vertical outer edge, which is polished, burnished,

50 or otherwise rendered ornamental. The de-

sign for the base-section also embraces horizontal rails l, one across the front and one across each end. These rails terminate at their ends in ornamental polygonal heads n, 55 and are connected with the body by curved arms o, which spring upward from beneath the plate k.

The third or grate section, C, is located immediately above the plate k, and is of such size that the plate extends beyond the same on all sides. At the front the section C has

two hinged doors, and also has a corresponding door at each end. The design for these doors embraces a substantially rectangular frame 65

with Gothic windows therein, each window-opening being encircled by a raised bead or flange, and the surface being ornamented by lines and figures therein, as shown. The forward corners of the section C, which are beveled or chamfered off, contain each a window-

70 opening, p, having an arched top. This window-frame projects beyond the body in the manner shown, and is closed ordinarily by a sheet of mica or similar transparent material. 75

The fire-pot section D forms an upward continuation of the section C, being of substantially the same form in horizontal section. The two are separated by a horizontal projecting belt or band, r, the edge of which is 80

substantially vertical, and the surface of which contains ornamental figures therein, as shown. The section D is also provided with beveled doors at the front, and a single door, s, at either side. The door-frames are substan-

85 tially rectangular in form. The upper outer corners are, however, rounded, as shown. The door contains two series of window-openings, t, having arched tops, one set of openings being arranged directly above the other. The 90

beveled corners of the sections are also provided with projecting window-frames similar to those in the section below, except that the windows are arranged in pairs, one directly above another. The outer surfaces of the 95

doors have ornamental lines therein, as shown. The upper portion of the section is rounded and drawn inward, whereby it is reduced in size.

Above the section D there is a horizontal 100 plate, E, projecting beyond the same, with overhanging edges, which are burnished or

otherwise rendered ornamental. This plate partakes of the general form of the body, being substantially rectangular, with beveled or chamfered corners.

5. Above the plate E is located the top or magazine section, F. This section, which is somewhat smaller horizontally than the section D, is made with perpendicular walls. It is substantially rectangular, and has the corners 10 chamfered or beveled, and each provided with a vertical semi-cylindrical projection, u, terminating in an ornament of the character represented. The outer surface is provided with ornamental figures therein, as shown. The 15 front face and the two end faces of the section F are provided with ornamental tiles x, bearing suitable figures, or with metallic panels in imitation of tiles.

Surmounting the section F there is a top 20 plate, G, of corresponding form, the edges of which are extended beyond the section F and dropped downward in the manner shown. This plate, which is usually burnished or polished on the edge, has a slight downward inclination on the top from the center toward the 25 several edges, and is in turn surmounted by the covering-plate H, of corresponding form.

Above the plate H there is located a horizontal bar or handle, I, supported by posts at 30 its end, the latter being made of the ornamental configuration represented in the drawings.

Having thus described my design, what I claim is—

35. 1. The design for a heating-stove, embracing the sections A, B, C, D, and E, substantially as shown.

2. The design for a base, embracing the plate a, with the bead b, the depending flange c, and 40 the legs e.

3. The design for an ash-pit section, embracing the substantially rectangular body with beveled corners, the end panels, f, corner panels, g, and front door, h.

4. The design for an ash-pit, embracing the 4 substantially rectangular body with the raised panels at the ends and the beveled corners with raised panels g thereon, the panels ornamented substantially as shown.

5. The design for the grate-section C, embracing the substantially rectangular body, the doors at the front side, the beveled corners, and the projecting windows p, as shown upon the said corners.

6. In a design for a heating-stove, a grate-section of substantially rectangular form in cross-section, having beveled corners and projecting windows p thereon.

7. The design for the fire-pot section, consisting of a substantially rectangular body, 6 the front and end doors, and the beveled corners with projecting windows thereon.

8. The design for the fire-pot section, embracing substantially the rectangular body with a contracted upper end, the beveled corners, projecting windows upon the said corners, and the doors upon the front and ends, said doors and windows having two series of openings, one above another.

9. The design for the top or magazine section, embracing the substantially rectangular body, the tiles upon the front and ends thereof, and the beveled corners provided with the rounded outwardly-projecting ornaments, as shown.

10. In a design for a heating-stove, the body-section of substantially rectangular form with beveled corners, the plate k, the three independent horizontal bars l, arranged with respect to the plate and body as described and shown.

NICHOLAS BRAYER.
